Specification for Design.

Patented Mar. 8, 1921.

Application filed June 21, 1920. Serial No. 390,663. Term of patent 14 years.

To all whom it may concern:

Be it known that I, HARRY H. KWATNEZ, a citizen of the United States, residing at Chicago, in the county of Cook and State of Illinois, have invented a new, original, and ornamental Design for a Lighting-Fixture Hanger, of which the following is a specification, reference being had to the accompanying drawing, forming a part thereof.

Fig. 2 is a bottom view of the same; and Fig. 3 is an end elevation.

I claim:

The ornamental design for a lighting fixture hanger, as shown. (Case 3).

In testimony whereof, I have hereunto signed my name in the presence of two subscribing witnesses.

HARRY H. KWATNEZ.
